ABSTRACT OF THE DISCLOSURE

Gasholder of the type having an annular side wall and a piston disposed therein with a curtain seal connected between the side wall and a smooth and tensioned and sinuous backstop surface mounted on the piston, the sinuous backstop surface having an effective circumference less than that of the inner surface of the side wall and the curtain seal having an initial effective circumference intermediate that of the side wall and the sinuous backstop surface.

This invention relates to dry-seal, piston-type gasholders and other fluid storage apparatus, of the particular type or kind that comprise a container provided with a cylindrical side wall, a vertically movable piston in the container that forms the top wall of the gas storage space of the apparatus, a seal for the space between the piston and the container side wall made of gas-tight fabric and constructed in the form of a flexible curtain suspended between and attached to the piston and to the container side wall and proportioned so as to provide for the rise and fall of the piston, and back up members or abutment surfaces disposed in such relationship with the curtain-like fabric seal that during the cycle of operations of the piston the abutment surfaces function as back stops that absorb pressure exerted on the seal by the gases confined in the storage chamber of the apparatus. Generally the portion of the container side wall located above the point where the fabric seal is attached to the wall is used to constitute an "outer" back stop that is located at the outer edge of the seal and which absorbs pressures exerted on the seal during the upward stroke of the piston, and at least one vertically movable "inner" back stop or abutment member of tubular or cylindrical form is arranged inside of the outer back stop in spaced, concentric relation with the same so as to absorb pressure exerted on the fabric seal during the downward stroke of the piston. If the fabric seal is constructed in the form of a relatively long or deep cylinder attached at one of its ends to the "outer" back stop formed by the container side wall and attached at its other end to the piston, the "inner" back stop will be formed by a tubular or cylindrical member rigidly combined with the piston and projecting upwardly from the same, and if the fabric seal is composed of two cylindrical sections, one of which is attached to the container side wall and the other attached to the piston, an additional vertically movable back stop of tubular or cylindrical form will be arranged between the piston and the container side wall and attached to the two sections of the seal in such a way that during the cycle of operations of the piston the additional back stop will coact with the back stop on the piston to back up the inner seal section (the one nearest the piston), and the additional back stop will coact with the abutment surface on the container side wall to back up the outer section of the seal (the one nearest the container wall), as disclosed in U.S. Patent No. 2,606,824, dated Aug. 12, 1952, to John W. Allen.

This type of gasholder with one outer and one inner back stop is shown in the prior patent to Wiggins, et al.

2

No. 2,723,908, and the instant invention is an improvement over the gasholders shown therein.

I have discovered that the proportioning of the circumference of the outer back stop and the inner back stop as described in the above patent is in error because making the inner back stop of the same effective circumference as the outer back stop will place the seal under tension substantially at all times so as to effect a permanent stretch to a length equal to the length of the outer back stop. Such lengthening of the seal due to undue stretching will, in a comparatively short time, result in the seal forming deleterious wrinkles which will materially reduce the life of the seal.

I have discovered that a proper proportioning of the effective length of the outer back stop to the effective length of the inner back stop in relation to the relaxed circumferential length of the seal will result in creating alternate compressions and tensions and thereby offset a permanent growth by a permanent compression of the seal and hence prevent such deleterious wrinkles. In normal operation, the seal will be held against the outer back stop about the same number of days per year as it is held against the inner back stop and this invention utilizes a long time held compression effect to counter-act a long time held tension effect. It is necessary to maintain a portion of the gap as a seal compressing portion as well as to maintain the other portion of the gap as a seal tensioning portion to reduce undue permanent lengthening, and I have found that if the percentage compressibility of a new seal for this type of gasholder is more than 2% of the circumferential seal length, then if the designed compression is held to less than 1%, the operation is a safe one to extend the operational life expectancy of a seal without deleterious wrinkles.

One object of the invention therefore is to proportion the circumferential length of this seal and the effective cylindrical length of a scalloped back stop surface or inner back stop in such a way that there will always be some percentage of compression of the seal when it is pressed against the inner back stop after a long period of service.

Another object of the invention is to provide an improved sinuous surface to constitute the inner back stop which will prevent any wrinkling when the seal is against this surface.

A further object of the invention is to provide an inner back stop comprising specially constructed and mounted plates so that the loads on the plates and the means for joining the plates will be resisted in the plates and the means as tension.

A further object of the invention is to mount these scalloped plates so that all the plates are identical and hence the plate tensions balance each other all around.

Still another object of the invention is to so design the steel plates of sinuous or corrugated structure and so that the attachments of the seal plates to each other are in completely accessible locations and can be performed by one man.

A further object of the invention is to provide a piston structure which facilitates the assembly of the posts and the plates in accurate predetermined positions.

The above and other objects of the invention are attained as described in connection with a preferred embodiment thereof, as disclosed in the accompanying drawings in which:

FIGURE 1 is a horizontal sectional view taken in the plane indicated by the line 1—1 in FIG. 3;

FIG. 2 is a fragmentary elevational view taken as generally indicated by the line 2—2 in FIG. 1;

FIG. 3 is a vertical sectional view taken as indicated by the line 3—3 in FIG. 2;

FIG. 4 is an enlarged portion of the section shown in FIG. 3;

FIG. 5 is a fragmentary perspective view illustrating the rolling of the seal in a loop as it moves from the inner back stop to the outer back stop or vice versa;

FIG. 6 is a fragmentary sectional view taken as indicated with the line 6—6 in FIG. 2; and

FIG. 7 is an elevational view of the fragmentary sectional view shown in FIG. 6 as viewed from the right thereof.

The gasholder of the present invention includes a cylindrical side wall 11, a bottom 12 and a roof, not shown, to form a completely enclosed container for a dry-seal piston-type gasholder. There is provided a piston 13 having a solid bottom wall 14 around which a circular angle or girder 16 is mounted and above which a circular framework is provided including vertical posts 17 and an upper circular angle or girder 18. The circular girder 18 has respective depending lugs 19 welded thereto which have a pair of apertures to receive fastening bolts (unnumbered) for the vertical posts 17 which at their bottoms are welded to brackets 20 extending upwardly from their welded connections to the bottom wall 14 of the piston 13. This circular framework comprises the first part of the inner back stop.

A rubberized fabric seal 21 is provided and is secured about the periphery of the circular girder 16 by a series of clamp bars 22 bolted to the girder 16, and, at its upper end, the seal 21 is secured by a series of clamp bars 23 to the side wall 11 of the gasholder. At both points of the attachment of the seal 21 to the piston 13 and to the side wall 11, care is taken to make the connection gas-tight. The seal 21 itself is a rubberized fabric of gas-tight character.

Of special interest is the construction and character of the outer wall of the piston 13 which forms the second part of the inner back stop for the seal 21. This outer wall is made up of a series of limber plates 26 which are constructed to provide a smooth continuous scalloped or sinuous surface at the outer edge of the piston 13. The curved ridges 26a of this surface extend vertically so that a vertically corrugated surface is presented as a back stop to the seal 21 and this is of a smooth continuous character. It will be seen that each plate 26 has its curved ridge 26a seated over one of the vertical posts 17 and then extends inwardly therefrom in concave fashion and the two edges of each plate 26 are provided with a right angle flange 27 which extends vertically and directed toward the center of the piston 13. The flanges 27 of adjacent plates 26 are secured together by a plurality of bolts 28, the dimensioning of the plates and the spacing of the posts 17 being such that these plates 26 are in tension when bolted together and correspondingly, the bolts 28 are also in tension. No gap is present where the edges of the plates 26 meet, and therefore the seal 21 lies smoothly as it crosses these edges. In effect therefore a smooth continuous corrugated or sinuous surface is presented as an inner back stop for the seal 21 and this surface including the corrugations has an average diameter of the circle C-3 which is shown in phantom lines in FIG. 4. This circle C-3 may be substantially equal to or slightly less (as shown) than the circle C-4 of the relaxed condition of the seal 21, i.e., when there is no gas present in the gasholder. Rectangular washers 30 are provided for each of the bolts 28.

It is seen therefore that the circumferential length of the fabric seal 21 when relaxed is less than the circumferential length of the outer back stop or gasholder side wall 11, and is greater than the effective circumferential length of the sinuous support or second part of the inner back stop carried by the piston 13. Therefore when the seal 21 is pressed against the gasholder side wall 11 (C-1) it will be under tension and a certain amount of stretch will occur, and corresponding when the seal 21 is pressed against the inner back stop (C-2) it will be under

5 a slight compression and a counteraction of the stretching will occur. This combination of alternate compression and tension of the seal 21 as the cycles of the piston 13 continue prevents a permanent lengthening of the seal 21 and allows no wrinkling of the seal 21 as occurs if it were continually under tension and continually stretched. By properly proportioning the circumferential length (C-4) of the seal 21 and the effective circumferential length (C-3) of the scalloped or sinuous surface formed by the plates 26, there will always be some percentage 10 of compression in the seal 21 when it is pressed against the sinuous part of the inner back stop and this compression will counteract the effect of a comparable percentage of tension when the seal 21 is pressed against the outer back stop after a similar period of service.

15 The desirable optimum condition is to have the compression effect in the shortening of the seal 21 balance the tension effect in the lengthening of the seal 21 so that additional years of wrinkle-free operation are provided. Referring to FIG. 4 there is shown a gap G between the inner surface of the outer side wall 11 of the gasholder and the outer surface of the piston 13 and this gap is termed the "operational" gap in which the seal 21 must work as the piston 13 rises and falls within the gasholder. 20 There is also indicated a second radial distance Gc, called the seal "compression" gap, which is the radial distance from the relaxed position of the seal 21 to the effective circumference of the scalloped back stop surface and, roughly, this compression gap Gc should be an amount 25 which is essential for the allowable compression of the seal 21 during operation of the gasholder. In general the circumference (C-4) of the seal 21 is made slightly greater than the effective circumference (C-3) of the scalloped back stop. When the seal 21 is relaxed, there is a 30 third radial distance Gt extending radially outward from the seal 21 to the inner wall 11 of the gasholder and this gap constitutes a seal "tension" gap, and Gt is an amount which is essential for the desired stretch of the seal 21 during the operation of the gasholder to balance the compression of the seal 21.

35 The construction of the sinuous inner back stop provides several advantages. In the first place it presents the convex surfaces of the vertically disposed plates 26 inwardly in order that the loads of the seal 21 may be 40 resisted as tension. Also the plates 26 are so joined that each plate 26 balances the tensions in the two adjacent plates 26, and therefore there is balanced tension in all the plates 26. This balanced tension transmits only radially directed forces to the supporting frame posts 17 around 45 which the plates 26 are mounted.

50 In assembly, the vertical seams of the plates 26 are completely accessible inside of the piston 13 and can be set in place by one man in an unobstructed area. Also in assembling these plates 26, they are temporarily supported by the bolts at the top of the posts 17 by the simple swingable attachment at each post 17 by means of a bolt 17a; and as the plates 26 are progressively joined at their vertical flanges 27 these flanges 27 are automatically pulled into vertical lines so that they fit controlled 55 by the level line of the holes in the posts 17 for the bolts 17a. This removes the necessity for the posts 17 to be perfectly plumb. The only necessary accurate location 60 for spacing of the posts 17 is at their top connections to the circular girder 18.

65 In operation, the construction of the sinuous part of the inner back stop is smooth and uninterrupted without any unsupported seal area, as found for example in a full length vertical slot into which the seal 21 might stretch out of control, and also, this smooth continuous surface induces the seal 21 to compress instead of wrinkling as every tiny area of the seal 21 is pressed against the back stop surface by the gas in the gasholders.

70 While I have shown and described a preferred embodiment of the invention, it is apparent that the invention is 75

capable of variation and modification from the form shown so that the scope thereof shall be limited only by the scope of the claims appended hereto.

I claim:

1. A gasholder comprising a substantially vertical cylindrical side wall, a vertically movable cylindrical piston therein spaced from said side wall, an annular flexible seal secured along one edge thereof in sealed relation to said side wall along a circular line intermediate the height thereof and secured along the other edge thereof in sealed relation to said piston along a circular line adjacent to the bottom thereof, and an annular fender structure mounted on said piston and extending upwardly therefrom and spaced from said side wall, said fender structure including a series of vertical circumferentially spaced posts mounted in a circular array on said piston, and a series of plates each having at least one vertically disposed smooth ridge disposed adjacent to one of said posts and having arcuate concave sections disposed on each side thereof, and means joining the adjacent vertical edges of said plates to provide a continuous sinuous outer surface for said fender structure, said outer surface being smooth and continuous at the ridges disposed at said posts and being smoothly concave between said ridges and across the junctures between adjacent plates.

2. The gasholder set forth in claim 1, wherein said plates are under tension whereby to urge said concave surfaces outwardly with respect to said piston.

3. The gasholder set forth in claim 1, wherein each of said plates has inwardly directed flanges on the vertical edges thereof, and said means securing said adjacent plates is a series of bolts holding said plates in tension.

4. A gasholder comprising a substantially vertical cylindrical side wall, a vertically movable cylindrical piston therein spaced from said side wall, an annular flexible seal secured along one edge thereof in sealed relation to said side wall along a circular line intermediate the height thereof and secured along the other edge thereof in sealed relation to said piston along a circular line adjacent to the bottom thereof, and an annular fender structure mounted on said piston and extending upwardly therefrom and spaced from said side wall, said fender structure including a series of vertical circumferentially spaced posts mounted on a circular array on said piston, a series of plates each having at least one vertically disposed smooth ridge disposed adjacent to one of said posts and having arcuate concave sections disposed on each side thereof, means joining the adjacent vertical edges of said plates to provide a continuous sinuous outer surface for said fender structure, said outer surface being smooth and continuous at the ridges disposed at said posts and being smoothly concave between said ridges and across the junctures between adjacent plates, the effective diameter of the outer surface of said fender structure being less than the effective diameter of the inner surface of said side wall, said annular flexible seal having a normal and unstretched effective diameter intermediate that of the outer surface of said fender structure and the inner surface of said side wall, whereby the pressure of the gas in said gasholder urges said seal against the

inner surface of said side wall to place said seal in tension when said piston is in the upper portion of the travel thereof and the pressure of the gas in said gasholder urges said seal against the outer surface of said fender structure to place said seal under compression when said piston is in the lower portion of the travel thereof, thereby alternately to place said seal under tension and compression as said piston moves with respect to said side wall and thus to prevent excessive permanent lengthening of the seal and to prevent wrinkling of the seal in use.

5. A gasholder comprising a substantially vertical cylindrical side wall, a vertically movable cylindrical piston therein spaced from said side wall, an annular flexible seal secured adjacent to one edge thereof in sealed relation to said side wall along a circular line intermediate the height thereof and secured adjacent to the other edge thereof in sealed relation to said piston along a circular line, and an annular fender structure mounted on said piston and extending upwardly therefrom and spaced from said side wall, the outermost portions of said piston and said fender structure lying within a cylindrical surface spaced from said side wall a predetermined distance to provide an operational gap therebetween, said fender structure including an outer sinuous surface having an effective diameter less than the inner diameter of said side wall but greater than said cylindrical surface while maintaining said operational gap, said annular flexible seal having a normal and unstretched diameter intermediate that of the inner surface of said side wall and said cylindrical surface, whereby the pressure of the gas in said gasholder urges said seal against the inner surface of said side wall to place said seal in tension when said piston is in the upper portion of the travel thereof, and whereby the pressure of the gas in said gasholder urges said seal against the outer surface of said fender structure to place said seal under compression when said piston is in the lower position of the travel thereof, thereby alternately to place said seal under tension and compression as said piston moves with respect to said side wall and thus to prevent excessive permanent lengthening of the seal and to prevent wrinkling of the seal in use.

6. The gasholder set forth in claim 5, wherein said flexible seal is formed of a rubberized fabric.

7. The gasholder set forth in claim 5, wherein said fender structure includes a series of vertical circumferentially spaced posts mounted in a circular array on said piston, and a series of plates mounted on said posts and providing vertically extending concave surfaces between said posts.
